STAPLING DEVICE

Desmond R. La Place, Beaver Falls, Pa., assignor
to Bocjl Corporation, Pittsburgh, Pa., a corpora-
tion of Delaware

Application November 14, 1939, Serial No. 304,360

29 Claims. (Cl. 1—49)

This invention pertains to stapling devices of the character wherein a wire staple is separated from a clip or row of staples and is driven from the device and is for a stapling device of improved construction especially designed for use in a hand implement of compact construction and is preferably of a construction such that it may be used either for stapling a plurality of loose sheets together or for stapling or tacking one or more loose sheets to a backing panel.

Numerous types of stapling machines have heretofore been constructed. Many of these are in the form of a plier in which the operation of stapling is effected by squeezing two handles of the implement together. Other common forms of such devices employ a pivoted arm on a stationary base with a plunger carried on the outer end of the pivoted arm. While such devices are satisfactory, they are necessarily quite large and such devices cannot be readily designed as pocket tools. Moreover, such devices are useful only for stapling and cannot be used for tacking purposes. According to the present invention there is provided a novel construction of stapling tool especially constructed to be embodied in a pocket-sized machine and which is of a shape and construction such as to render it more convenient for many purposes than present types of stapling equipment. According to the preferred embodiment of my invention, the machine is further so constructed that it may be interchangeably used as a stapling device or as a tacking device, and as a tacking device it may be easily held and operated in one hand leaving the other hand of the operator free to steady and hold the paper or other object which is to be tacked in place on the panel or backing to which it is to be secured. In this respect it is well adapted for use in drafting rooms and similar places where a quick and convenient means of tacking the paper to a backing board or panel is needed. The present invention further provides a tool which, while being mechanically satisfactory, can be cheaply constructed so as to enable a combined stapling and tacking device to be provided at very moderate cost.

The invention may be readily understood by reference to the accompanying drawings in which

Figure 1 is a side elevation of a full-sized embodiment of a stapling device embodying my invention;

Figure 2 is an exploded view on a larger scale of the device shown in Figure 1, the view being a

longitudinal vertical section and the several parts being separated;

Figure 3 is a view similar to Figure 2 showing a longitudinal section through the assembled device, the parts being in a normal position;

Figure 3a is a view similar to the lower portion of Figure 3 showing the position of the parts when the driver has been pushed down.

Figure 4 is a view similar to Figure 3 with certain parts of the machine omitted, the parts being in the position to which they are moved for charging or loading a clip of staples into the machine;

Figure 5 is a side elevation of the magazine member removed from the rest of the device;

Figure 6 is a top plan view of the part shown in Figure 5;

Figure 7 is a transverse section in the plane of line VII—VII of Figure 2;

Figure 8 is a similar transverse section in the plane of line VIII—VIII of Figure 2;

Figure 9 is a side elevation of a modified form of stapling device having a magazine adapted to contain several clips or strips of staples at one time and having means for progressively advancing these clips as they are consumed;

Figure 10 is a longitudinal section through the device shown in Figure 9; and

Figure 11 is a transverse longitudinal section through Figure 9 at right angles to Figure 10.

Referring first to the construction illustrated in Figures 1 to 8 of the drawings, the machine comprises several telescoping parts some of which are normally relatively movable to the others and some of which are normally in fixed relation to one another. The device comprises a main barrel member 2 which is illustrated as having a transverse partition 3 therein intermediate its ends. The upper end of the barrel is closed with a removable cap 4. The purpose of this arrangement is to provide an enclosed chamber 5 for receiving and holding spare clips of fasteners. Received within the interior 6 of the barrel at the other side of the partition 3 is a compression spring 7. Fitted into the open end of the barrel 2 is a cylindrical body 8 having a reduced end portion 8a. The spring 7 fits about the end portion 8a and bears against the end of the cylindrical body 8. The cylindrical body 8 is provided at its lower end with a transverse groove 9, the body having a longitudinally extending recess 10 therein. Formed in the body 8 between the slot 10 and the recess 9 are shoulders 11.

Passing through the reduced portion 8a of the cylindrical body is a pin 12 that serves as a pivot

for an inverted T-shape follower member 13, this follower member having a crossbar 13a at its lower end as viewed in Figure 2 that fits within the slot 9. A coiled compression spring 14 housed within the cylindrical body bears against the follower 13 to urge it toward the right as viewed in Figure 2. This same spring bears against the flange 15 of a snap pin 16 for normally urging the snap pin 16 outwardly, that is, toward the left as viewed in Figure 2.

The transverse groove 9 is adapted to constitute a magazine to receive a row or clip of staples, designated A in Figure 3. The follower 13 is adapted to yieldably bear against the end of a clip of staples in the magazine and to propel the clip toward the right as viewed in Figure 3 as successive staples are removed.

As shown in Figure 5, the exterior of the cylindrical body 8 is provided with a longitudinally extending recess 17. A flap strip of metal 18 lies in this recess 17 and the upper end portion 18a thereof extends up into the recess 6 in the barrel 2. The innermost end of the portion 18a is provided with a stud 19 which, as shown in Figure 3, normally projects through an opening 20 in the barrel member 2. This stud serves to connect the member 18 with the barrel member 2 so that any longitudinal movement of the barrel 2 is transmitted to the strip 18. The strip 18 constitutes the driver for separating the staples from the clip and forcing them through the material that is to be fastened or tacked. The driver 18 may be readily disconnected from the barrel 2 when the device is being taken apart by pushing the stud 19 inwardly through the hole 20, the strip 18 being of resilient metal in order to permit the end to be sprung in this way. The driver 18 also carries a reversely projecting stud 21 thereon intermediate the ends thereof which stud cooperates with a shoulder at 22 on the cylindrical member 8 for limiting relative movement of the driver with respect to the cylindrical body 8 in one direction.

In addition to the push-pin 16 the member 8 also has a push-pin 23 thereon secured thereto by a leaf-spring 24 received within a groove 25 in the side of the cylindrical member 8. The lower end of the barrel 2 is slidably fitted into a tubular guide member 26. This guide member has an upper tubular portion 26a in which the end of the barrel 2 has a sliding fit, and at the base of the portion 26a is an internal shoulder 26b. This shoulder 26b is adapted to contact with the end of the barrel 2 to limit the relative sliding movement of the barrel in the guide member 26. Below the portion 26a the body 26 has a well or chamber 26c of lesser internal diameter into which the end of the cylindrical body 8 fits. The lower end of the guide member 26 is closed by a transverse partition 26d. Through this partition is a narrow slot 26e. This slot is of a dimension such as to enable the end of the driver 18 to slide therethrough and it is through this opening that staples are driven as they are separated from the clip in the magazine. When the parts are assembled as shown in Figure 3, the push-pin 23 projects through a hole 26f in the member 26 whereby the guide member 26 is releasably secured to the cylindrical body 8. When the member 26 is so secured to the member 8, the partition 26d at the end of the body 26 cooperates with the end of the body 8 to close the groove 9 in which the clip of staples is positioned to thereby hold the staples in position in the device. As will be clearly apparent from an examination

of Figure 3, the row of staples designated A is confined between the partition 26d and the shoulders 11 so that the clip of staples cannot become displaced in a vertical direction. The follower 13—13a bears against one end of the clip of staples while the other end of the clip of staples is pressed against the inner wall of the member 26. When the parts are in the position shown in Figure 3, the end of the driver 18 is over the slot 26e and is over that staple in the clip which is being pressed against the inner surface of the member 26. When the parts are in the position shown in Figure 3, the application of pressure to the end of the barrel 2 will cause this barrel to slide inside the guide member 26 until the end of the barrel 2 hits the shoulder 26b. During this movement of the barrel 2 the driver 18 will engage the staple at the right-hand end of the clip and will force the staple through the slot 26e where it will be used either for stapling or tacking as will be hereinafter more fully explained. Upon release of pressure from the barrel 2, the spring 7 will force the barrel back to the normal position shown in Figure 3. When the end of the driver 18 has cleared the clip of staples, the follower 13—13a will operate to slide the clip toward the right as viewed in Figure 3, thus bringing the next staple into position to be driven. The upward movement of the barrel 2 under the influence of the spring 7 will be stopped when the stud 21 contacts portion 22 of the cylindrical member 8. When this stud hits the portion 22, the driver 18 cannot move up any further and since the driver 18 is connected to the barrel 2 through the pin 19, the barrel 2 cannot move any further. The sliding telescoping movement of the barrel with reference to the guide 26 is therefore limited in one direction by the internal shoulder 26b in the member 26 and in the other direction by the stud 21 on the driver.

Slidably fitted over the lower end of the guide member 26 and detachably carried thereon is an anvil member in the form of a cylindrical cup 27 having a closed lower end 28 and having a transverse slot 29 therein. Also formed in the side wall of the member 27 is an elongated opening 30. The pin 23 which connects the cylindrical member 8 to the guide member 26 also extends through the slot 30, and to remove the member 27 from the end of the tool it is merely necessary to depress the pin 23 sufficiently to enable the member 27 to be pulled off endwise. Secured in the bottom of the member 28 is a leaf-spring 31 that normally connects with the bottom 26d of the guide member 26 and which serves to normally urge the member 27 in a direction away from the member 26, but such movement is limited, of course, by the pin 23 engaging the end of the slot 30. Also secured in the bottom of the member 27 is an anvil element 32 having two opposed grooves 33 therein in line with the slot 26e in the guide member 26. The pin 23 engaging in the slot 30 not only serves to hold the member 27 on the end of the guide member but it also serves to hold the member 27 against rotation relatively to the member 26 so that the recesses 33 are always in proper alignment with the slot 26e and with the ends of any staple that is projected through the slot.

The transverse slot 29 in the end member 27 is designed to receive the sheets of paper to be stapled together. By reason of the fact that the end member 27 has a limited longitudinal movement on the end of the tool through the interengagement of the pin 23 in the slot 30, the end member automatically adjusts itself to the thick-

ness of the papers to be stapled. If there are only one or two sheets of thin paper to be stapled, the anvil member 32 can approach much closer to the end of the guide member 26 than where the papers to be stapled are the full thickness of the slots 29. It is of course desirable that the anvil 32 move closer to the end of the staple-driving means when the papers to be stapled are thin. When it is desired to use the tool as a tacking device, the pin 23 is depressed sufficiently to release the end member 27 to enable the end member to be removed.

It will be noted in Figure 3 that the snap pin 16 is normally compressed inside the barrel 2. The barrel 2 is provided with a hole 16a into which the pin 16 may snap under certain conditions, but this hole is positioned sufficiently far back on the barrel so that when the end of the barrel hits the shoulder 26b in the guide 26, the hole 16a and the pin 16 will still be out of register and the pin confined by the barrel. Thus it is impossible for the pin 16 to enter the hole 16a as long as the guide member is in place at the end of the barrel.

The condition under which the pin 16 will enter the hole 16a is shown in Figure 4. This occurs only when the device is taken apart for the insertion of a new cartridge or clip of fasteners. When it is necessary to insert a new cartridge or clip of fasteners, the pin 23 is depressed first to remove the end member 27 and then to enable the guide member 26 to be slid off the end of the barrel 2. When the tool is being taken apart in this way to insert a clip of fasteners, it is held in an upright position. After the two parts 26 and 27 have been removed, the operator pushes the member 8 down into the barrel 2 until the pin 16 snaps through the hole 16a in the barrel. This locks the member 8 against being moved out under the compression of the spring 7. Such movement of the member 8 inwardly causes the driver 18 to extend over one end of the groove 9. While the parts are in this position, the follower 13-13a is moved to the right as viewed in Figure 4 and the clip of cartridges A is inserted. The clip of cartridges is thus engaged at one end by the follower 13-13a while its other end is forced against the driver 18 and held in the groove by the driver. With the parts in this position, the guide member 26 is put back onto the end of the barrel and the button or push-pin 16 is forced in. When it has been forced in a sufficient distance, it will be disengaged from the hole 16a whereupon the spring 7 will expand to force the parts back to the position shown in Figure 3. It will thus be seen that for the purpose of loading the tool, the parts are temporarily forced into a position where the driver 18 extends across one end of the magazine to prevent the clip of staples from being moved endwise out of the magazine by the action of the follower until the guide member 26 can be restored to the end of the barrel 2. When the guide member has been restored to the end of the barrel and the parts have been returned to the normal position shown in Figure 3 through the releasing of pin 16 and the action of spring 7, the guide 26 then limits the transverse movement of the clip of staples, and the driver is retracted to a position back of the clip of staples.

From the foregoing description it is believed that the operation of the tool will be apparent. Assuming a clip of cartridges to be charged into the device and the parts to be in the normal position shown in Figure 3, if the device is to be used for stapling papers or other loose sheets together,

the edges of the pieces to be stapled are inserted in the slot 29 while the end 28 of the tool is placed on some support or while the tool is held between the thumb and fingers of one hand. Pressure is 5 then applied to the upper end of the barrel 2 forcing the barrel and the driver 18 toward the anvil 32. The driver 18 engages the end staple in the clip, forces it through the slot 26e and through the papers or other pieces to be fastened and the ends of the staple engaging in the slots 33 in the anvil are turned inwardly and mashed down. Upon release of pressure from the end of the barrel, the spring 7 returns the parts to their normal position and the follower 13-13a moves the clip 10 of staples toward the right as viewed in Figure 3 to bring the next staple into position to be driven. By reason of the fact that the anvil-carrying element floats on the end of the tool, the parts automatically adjust themselves for the stapling 15 of a thick or thin sheath of papers. When using the device for tacking as distinguished from stapling, the end member 27 of course is removed. The end of the guide element 26 is then placed against the sheet to be tacked to a supporting 20 panel and pressure is applied to the barrel or plunger to drive the staple. The staple in this case, instead of engaging an anvil, is driven all the way into the supporting panel back of the sheet being tacked in place. In putting up posters on bulletin boards or on walls, the device may 25 be conveniently held in the clenched hand of the operator and the staples can be rapidly and efficiently driven.

In the modification shown in Figures 9, 10 and 35 11, arrangement is made for holding several clips of staples in the device at one time, the arrangement being such that as one clip of staples is exhausted, another may be advanced into position to be used up. In this modification the device is 40 illustrated as being rectangular in cross section rather than circular. In this construction there is an outer casing or shell 35 corresponding to the barrel member 2. Slidably positioned within this shell is a magazine element 36 corresponding to the member 8 of Figure 2. This member 36 has an extension 36a along one side thereof and it has side plates 36b. Between the side plates 36b is a magazine designated generally as 37 into which a number of clips of staples designated A are placed. The part 36a closes the magazine along its one side. Secured to the inner wall of the shell 35 is a strip 38 which constitutes the driver, this element corresponding to the member 18 of Figure 2. In the magazine between the spaced-apart plates 36b there is a follower or pusher plate 39 which bears against the innermost strip of clips. On the inner surface of this plate is a lug 40. Passing transversely through this lug is a double-ended resilient push-pin designated generally as 41 and comprising two parts, one being a member 41a having a flange 41b and a post 41c thereon. The other part of the double push-pin comprises a member 41d having a flange also designated 41b and having a sleeve 41e. The outer terminals of the push-pin extend through longitudinal slots in the shell 35. Interposed between the two members is a compression spring 42. The arrangement is such that when the two pins 41a and 41d are squeezed together, the flanges 41b may move inwardly to the extent permitted by the post 41c, and when pressure is released from the pins, the device will expand restoring the flanges 41b to their original position. The side plates 36b of the magazine have a longitudinal slot 43 therein, and on the inner face of the plates 36b adja-

cent the slot are a series of recesses 43a to receive the flanges 41b. The arrangement is such that when a clip of staples has been used and it is necessary to advance another strip into position to be used, the double-ended pin 41 is compressed disengaging the flanges 41b therefrom from the recesses 43a in which they are located. When the pin has been so compressed, it may be moved to the next notch or recess, this movement of course being transmitted to the follower plate 39 and to all of the clips of staples remaining in the magazine so that the row of staples most remote from the follower plate is forced down to the end of the magazine. The follower plate may thus be moved in a step-by-step manner as the several clips are used and it may be locked in each position to which it is moved.

Releasably secured to the lower end of the magazine 36 is a guide element 45 of a construction generally similar to the element 26 in the form shown in Figure 2. The guide member 45 has an end wall 45a which forms a bottom for the magazine chamber and which has a slot 45b therethrough in line with the driver 38. The end of the casing 35 is slidably fitted into the guide member 45. Relative sliding movement between the casing or plunger member 35 and the guide member 45 is limited in one direction through the engagement of a block 46 within the upper end of the casing with the top of the magazine element 36. Compression springs 47 are provided between the end of the casing 35 and the top of the block 36 for returning the casing to a normal position after it has been compressed to drive a staple. The upward movement of the casing 35 under the influence of the springs 47 may be restored in any suitable manner as for example, by the provision of a limiting pin 48 carried on a leaf-spring 49 on the exterior of the guide which pin projects through the wall of the guide and rides in a slot 50 in the shell 35.

For propelling the row of clips over toward the right as viewed in Figure 10 as the staples are consumed, there is shown a follower in the form of a flexible resilient flat metal strip 51 one end of which bears against the lowermost clip of staples and the other end of which has a plunger 52 thereon which is in a cylindrical chamber 53 in the upper end of the magazine block 36. Within the chamber 53 is a compression spring 54 which tends to push the plunger 52 to the left and thereby propels the opposite end of the strip 51 to the right. The block 36 has a groove down one face thereof to receive the flexible strip, this groove being indicated at 55. The outer casing 35 has a longitudinal slot at 56 and there is a button 57 on the strip 51 that projects through this slot. The arrangement is such that as staples are removed from the right-hand end of the bottom clip in the magazine, the spring 54 functions to cause the clip to be moved toward the right. When a clip of staples has been exhausted, the button 57 is used to move the flexible follower strip 51 to a retracted position against the compression of the spring 54. When the follower strip has been retracted, the follower or pusher 39 is operated in the manner previously described to advance the next clip into a position to be used.

In order that the next to the lowermost clip of staples in the magazine will not drop down as the bottom clip is being consumed, the sides of the magazine are formed with slots therein, and leaf-springs 58 are provided in these slots, the terminals 58a of these springs bearing against

the next to the bottom clip. These springs provide sufficient friction against the clip against which they bear to hold it from dropping down until the pusher 39 is operated.

Removably carried on the lower end of the guide member 45 is an end member 60 having an anvil 61 therein and having a horizontal slot 62 in it, this slot being provided to receive the papers or other sheets to be stapled together. The end member 60 is mounted on the end of the guide 45 in a similar way that the corresponding member is secured to the bottom of the device of Figure 1 so as to have a limited vertical movement relative to the guide member 45 and so as to be removable when the device is to be used for tacking instead of stapling.

In operation the modified construction is used the same as the device first described. It may be interchangeably used as a stapling device or as a tacking device by the application or removal of the end member. It can be held in one hand, the same as the form previously described, and squeezed while the papers to be stamped are held in the other hand and it can be used on a table or other firm surface and worked in the manner of a desk type of stapling device. When one clip of cartridges has been used, the follower strip 51 is slid back to the end of the magazine and the pusher 39 is moved forward one notch to force the next clip of staples into place.

In the modification as in the preferred form, there is a plunger comprising a shell having a driver for driving the staples telescopingly engaged with a guide member, and there is a magazine member completely housed within the shell and guide member and carried by one of these members, this magazine having means for moving a clip of staples transversely of the longitudinal axis of the tool. Both forms of the device are compact and they are simple and easy to operate, and the parts are so constructed as to be relatively cheap.

While I have illustrated and described certain preferred embodiments of my invention, it will be understood that the device may be otherwise constructed and that various changes and modifications may be made therein within the contemplation of my invention and within the scope of the following claims, and that the magazine arrangement for successively advancing clips of staples may be advantageously employed in other forms of stapling machines.

I claim:

1. A stapling device comprising telescoping guide and plunger members, and a staple-holding and feeding unit arranged for holding and feeding a row of staples transverse to the longitudinal axis of the device housed within said members, said members being axially slidable relatively to each other.
2. A stapling device comprising tubular guide and shell members telescopingly engaged and relatively movable in an axial direction, a staple holding and feeding means within one of said members, and a driver on the other of said members movable upon the telescoping movement of the members transversely across one end of the staple holding means.
3. A stapling device comprising slidably telescoped guide and plunger members movable relatively to one another in the direction of their longitudinal axes, a staple-holding magazine housed within said members, staple-feeding means on said magazine, and a longitudinally extending driving member on the plunger movable

with the plunger transversely to staples contained within the magazine.

4. A stapling device comprising a plunger member, a guide member, a staple-feeding and holding means housed between said members arranged for holding and feeding a row of staples transverse to the longitudinal axis of the device, said guide and plunger members being relatively movable in an axial direction, and an anvil member telescopingly mounted on the guide member movable longitudinally in an axial direction with respect to the guide member.

5. A stapling device comprising a plunger member, a guide member, a staple-feeding and holding means housed between said members, said guide and plunger members being relatively movable in an axial direction, an anvil member telescopingly movable on the guide member movable longitudinally with respect to the guide member, and means for detachably securing said anvil member to the guide member, said device being completely operable to drive a succession of staples when the anvil member is removed as well as when it is secured in place.

6. A stapling device comprising tubular guide and shell members telescopingly engaged and relatively movable in an axial direction, a staple holding and feeding means within one of said members, a driver on the other of said members movable upon the telescoping movement of the members transversely across one end of the staple holding means, and an anvil member slidably mounted on one of said members for relative movement in an axial direction and having a transverse slot therein for the reception of papers to be stapled.

7. A stapling device comprising a plunger member in the form of a hollow shell, a guide member telescopingly engaged for relative endwise movement, a magazine member in the shell and guide members having a transverse chamber for receiving and holding a clip of staples, resilient means movable along the chamber for engaging one end of a clip of staples positioned in the magazine, the guide member forming a closure at the other end of the chamber to limit the endwise movement of such clip of staples, and a driver on the plunger member movable upon relative longitudinal movement of the guide and plunger members along the inner surface of the guide member across the end of the clip of staples so confined, the driver being of a dimension such as to engage a single staple at the end of said clip, the guide member being provided with an axially extending opening in line with the driver and through which the staple detached from the clip may be driven.

8. A stapling device comprising a plunger member in the form of a hollow shell, a guide member telescopingly engaged for relative endwise movement, a magazine member in the shell and guide members having a transverse chamber for receiving and holding a clip of staples, resilient means movable along the chamber for engaging one end of a clip of staples positioned in the magazine, the guide member forming a closure at the other end of the chamber to limit the endwise movement of such clip of staples, and a driver on the plunger member movable upon relative longitudinal movement of the guide and plunger members along the inner surface of the guide member across the end of the clip of staples so confined, the driver being of a dimension such as to engage a single staple at the end of said clip, the guide member being provided with an axially

extending opening in line with the driver and through which the staple detached from the clip may be driven, and an end member on the guide member having a limited longitudinal movement relative to the guide member and having a transversely extending slot therein into which articles to be stapled may be inserted, said end member having an anvil therein adjacent the slot and in line with the driver.

9. A stapling device comprising a plunger member in the form of a hollow shell, a guide member telescopingly engaged therewith for relative endwise movement, a magazine member within the shell and guide members having a transverse chamber for receiving and holding a clip of staples, resilient means movable along the chamber for engaging one end of a clip of staples positioned in the magazine, the guide member forming a closure at the other end of the chamber to limit the endwise movement of such clip of staples, and a driver on the plunger member movable upon relative longitudinal movement of the guide and plunger members along the inner surface of the guide member across the end of the clip of staples so confined, the driver being of a dimension such as to engage a single staple at the end of said clip, the guide member being provided with an axially extending opening in line with the driver and through which the staple detached from the clip may be driven, and an end member on the guide member having a limited longitudinal movement relative to the guide member and having a transversely extending slot therein into which articles to be stapled may be inserted, said end member having an anvil therein adjacent the slot and in line with the driver, said end member being removably secured to the guide member whereby the device may be interchangeably used as a stapling or tacking machine.

10. A stapling device comprising a plunger member in the form of a hollow shell, a guide member telescopingly engaged for relative endwise movement, a magazine member in the shell and guide members having a transverse chamber for receiving and holding a clip of staples, resilient means movable along the chamber for engaging one end of a clip of staples positioned in the magazine, the guide member forming a closure at the other end of the chamber to limit the endwise movement of such clip of staples, and a driver on the plunger member movable upon relative longitudinal movement of the guide and plunger members along the inner surface of the guide member across the end of the clip of staples so confined, the driver being of a dimension such as to engage a single staple at the end of said clip, the guide member being provided with an axially extending opening in line with the driver and through which the staple detached from the clip may be driven, and an end member on the guide member having a limited longitudinal movement relative to the guide member and having a transversely extending slot therein into which articles to be stapled may be inserted, said end member having an anvil therein adjacent the slot and in line with the driver, said magazine having a storage chamber therein extending inwardly from said transverse chamber for receiving and holding reserve clips of staples and a pusher for progressively moving the clips of staples into the chamber as the clips are exhausted therefrom.

11. A stapling device comprising telescoping guide and plunger members, a staple-holding and feeding unit housed within said members,

said unit having a magazine therein for holding a plurality of superimposed clips of staples, and means for progressively advancing successive clips into position to be engaged by the feeding means.

12. A stapling device comprising a plunger member in the form of a hollow shell, a guide member telescopingly attached to the shell for relative endwise movement, a magazine element within said members having a chamber therein adapted to receive and hold a plurality of superimposed clips of staples therein, said guide member forming an enclosure for closing the end of said chamber to retain the several clips in contacting superimposed relation in the chamber, a pusher in said chamber for progressively pushing the clips toward the guide member, a feeder associated with the magazine for sliding that clip which is nearest the guide member endwise toward a driver, and a driver on the plunger member for advancing the successive staples from the clip so positioned and ejecting them from the end of the guide member.

13. A stapling device comprising telescoping guide and plunger members, means carried by the guide member providing a transverse staple-receiving chamber, yieldable means in said chamber for engaging a row of clips in said chamber for urging them transversely of the device into engagement with a wall of the guide member, the end of the guide member having an opening therein, and a driver on the plunger member positioned to engage that clip in the magazine which is pressed against said wall of the guide member to force it through said opening upon relative longitudinal movement in one direction between the plunger and the guide member.

14. A stapling device comprising an outer shell having a strip secured thereto and projecting from one end thereof forming a driver, a guide member at the end of said shell into which the driver normally projects and removably secured thereto in such manner that relative longitudinal movement may occur between the shell and the guide member, a staple-holding and feeding unit inside said guide and shell members, said unit having a transverse groove in one end thereof for forming a magazine to receive a clip of staples, said unit also having a spring-actuated follower for urging a clip of staples in said groove toward said driver, and means for releasably holding said staple-holding and feeding unit in the shell when the guide member is removed from the shell and in a position such that the end of the driver projects across said groove to provide an abutment for confining the clip of staples against movement under the action of said follower when said guide member is removed from the shell.

15. A stapling device comprising an outer shell having a strip secured thereto and projecting from one end thereof forming a driver, a guide member at the end of said shell into which the driver normally projects and removably secured thereto in such manner that relative longitudinal movement may occur between the shell and the guide member, a staple-holding and feeding unit inside said guide and shell members, said unit having a transverse groove in one end thereof for forming a magazine to receive a clip of staples, said unit also having a spring-actuated follower for urging a clip of staples in said groove toward said driver, and means for releasably holding said staple-holding and feeding unit in the shell when the guide member is removed from the shell and in a position such that the end of the driver

projects across said groove to provide an abutment for confining the clip of staples against movement under the action of said follower when said guide member is removed from the shell, said last-named means comprising a latch pin which is ineffective when the parts are in a normal operating position with the guide on the end of the shell and with the staple-feeding and holding member against said guide.

16. A stapling device comprising an axially aligned plunger, magazine, guide and anvil elements some of which are movable longitudinally relatively to the others, the plunger element having a driver thereon and the magazine element having means for progressively feeding a transversely arranged row of staples transversely of the structure toward the driver element.

17. A stapling device comprising an axially aligned plunger, magazine, guide and anvil elements some of which are movable longitudinally relatively to the others, the plunger element having a driver thereon and the magazine element having means for feeding a row of staples transversely of the structure toward the driving element, there being compression springs between some of said elements to maintain them in normal relation to one another, and means for confining said parts against separation under the action of said springs.

18. A stapling device comprising a shell-like plunger member having a driver thereon, a guide member telescopingly engaging one end of said shell-like member and with which said member cooperates, said shell and guide members being relatively movable, a staple-holding and feeding unit within said members and comprising a body having a transverse chamber at one end thereof forming a magazine to receive a clip of staples, said end of the body normally contacting with and being closed by the guide member, and a compression spring interposed between said body and said shell for resiliently urging the shell in a direction away from the guide member.

19. Stapling means comprising an axially aligned shell, staple-feeding and guide members, the first and last of said members being telescopingly engaged for relative sliding movement and the second of said members being interposed between the first two and being contained within the first two, means on the second of said members for receiving a row of staples and holding it in a transverse position, a feeder movable transversely of the longitudinal axis of said assembly for feeding said row of staples along the magazine, and a plunger on the first of said members for successively engaging staples of a row of staples so held for feeding them endwise through the guide member.

20. Stapling means comprising an axially aligned shell, staple-feeding and guide members, the first and last of said members being telescopingly engaged for relative sliding movement and the second of said members being interposed between the first two and being contained within the first two, said second member having a transverse magazine therein for receiving and holding a clip of staples, a feeder movable transversely of the longitudinal axis of said assembly for feeding said clip of staples along the magazine, a plunger on the first of said members for successively engaging staples of a clip of staples so held for feeding them endwise through the guide member, and a compression spring between the first and second members.

21. A stapling device comprising telescoping guide and plunger members connected together for relative sliding movement, a staple-holding and feeding unit housed within said members, said staple-holding and feeding unit comprising means for progressively moving a plurality of superimposed rows of preformed staples in one direction and means for progressively moving a single row of staples in the unit crosswise of the direction in which they are moved by said first means, and a driver on the plunger member for removing and ejecting staples one at a time from the row which is so moved.

22. A stapling device comprising telescoping guide and plunger members, means associated with the plunger member providing a magazine for receiving and holding a plurality of superimposed rows of staples, means in the magazine for moving all of said preformed staples in the direction of the longitudinal axis of the stapling device, means at one end of the magazine for moving the endmost row of staples transversely of the longitudinal axis of the device, and a driver on the plunger for progressively engaging the staples on the row so moved and ejecting them.

23. A stapling device comprising a magazine for receiving and holding a plurality of superimposed rows of preformed staples, means for feeding one of the superimposed rows of staples longitudinally with respect to the other rows, means in the magazine for moving one of the plurality of superimposed rows of staples to position another row to be engaged by the last-named means, and a driver for successively driving individual staples from the row as it is advanced by the feeding means.

24. A stapling device comprising a magazine for receiving and holding a stack of superimposed rows of preformed staples, feeding means for moving the endmost row of the stack of superimposed rows longitudinally with respect to the other rows, means in the magazine for moving the stack of staples to advance an endmost row to be engaged by the feeding means, and a driver for successively driving individual staples from the single row advanced by the feeding means.

25. A staple device comprising a magazine for receiving and holding a plurality of superimposed rows of preformed staples in vertical arrangement, means for feeding the lowermost row of staples horizontally with respect to the other rows to successively advance individual staples, means in the magazine for moving all of the rows

vertically to position the endmost row in position to be engaged by the last-named feeding means, and a driver for driving staples from the endmost row as it is advanced by the feeding means.

26. A stapling device comprising a driver and a staple guide, a feed mechanism for moving a row of staples in a direction perpendicular to the driver to deliver the staples of the row to the guide, a housing providing a magazine to hold several rows of staples in superimposed relation above the feed mechanism, and means for moving the superimposed rows of staples toward the feed mechanism in a direction parallel with the driver.

27. In a stapling machine, a vertical storage magazine for stacking staple strips in superimposed relation, a magazine track providing a raceway for a single strip of staples, and a feeding device positioned in operative relation with said track, said feeding device being adapted for moving the lowermost strip from a higher to a lower vertical plane defined by said track, and means for actuating said feeding device.

28. In a stapling machine, a storage magazine for receiving a plurality of rows of staples in which the several rows contact one another, a guide at one end of the magazine for receiving the row of staples at such end of the magazine, means for feeding said row of staples along said guide, means for feeding the rows of staples in the magazine toward said guide whereby the rows of staples may be successively delivered to the guide to be consumed, and means for restraining the movement of the rows of staples in the magazine toward the guide whereby the row in the guide must be consumed before the next row will be delivered to the guide.

29. In a stapling machine, a storage magazine for receiving a plurality of rows of staples in which the several rows contact one another, a guide at one end of the magazine for receiving the row of staples at such end of the magazine, means for feeding said row of staples along said guide, means for feeding the rows of staples in the magazine toward said guide whereby the rows of staples may be successively delivered to the guide to be consumed, and means for resiliently engaging the row of staples next to the one in the guide for restraining the movement of said row of staples toward the guide, whereby said row is restrained from engaging the guide until the row in the guide has been completely consumed.

DESMOND R. LA PLACE.

CERTIFICATE OF CORRECTION.

Patent No. 2,328,983.

September 7, 1943.

DESMOND R. LA PLACE.

It is hereby certified that error appears in the printed specification of the above numbered patent requiring correction as follows: Page 1, first column, line 22, for "canont" read --cannot--; page 4, second column, line 23, for "stampled" read --stapled--; and that the said Letters Patent should be read with this correction therein that the same may conform to the record of the case in the Patent Office.

Signed and sealed this 7th day of December, A. D. 1943.

(Seal)

Henry Van Arsdale,
Acting Commissioner of Patents.
